Philip A. Senell
Attorney

UNITED STATES PATENT OFFICE.

JOHN RETZLAFF, OF OMAHA, NEBRASKA.

WINDOW FASTENER.

Application filed April 20, 1925. Serial No. 24,607.

The invention relates to window fasteners and has for its object to provide a device of this character which is carried by the side rails of a sash, and cooperates with a window frame in the sash groove for holding the sash in various positions against movement, thereby allowing a sash to be raised or lowered for ventilating purposes, and at the same time holding the sash against movement sufficiently to allow unauthorized persons to enter through the window.

A further object is to provide a sash holding device comprising a plate carried by the inner side of the sash and arching a recess in the face of the sash and provided with a notched bar cooperating with the plate, vertically disposed overlapping rock levers carried by the plate and controlling pivoted window frame engaging members through links connected to the window frame members and the rock levers and link connections between the overlapped ends of the rock levers and the notched bar, said notched bar forming means whereby the window frame engaging member may be moved into and out of engagement with the window frame. Also to provide latching means carried by the plate and cooperating with the notched bar for positively holding said notched bar against movement.

A further object is to provide spring means cooperating with the overlapped rock levers for normally maintaining the pivoted window frame engaging members in inoperative position.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:—

Figure 1 is a vertical longitudinal sectional view through the side rail of a window sash showing the fastener applied thereto.

Figure 2 is a perspective view of the window fastener plate.

Figure 3 is a horizontal sectional view taken on line 3—3 of Figure 1.

Referring to the drawing, the numeral 1 designates the vertical side rail of a conventional form of window sash, and 2 a portion of a conventional form of window frame. Secured to the inner side of the 60 sash rail 1 by means of screws 3, which extend through the flanges 4 and 5, thereof is a plate 6, and which plate is preferably counter sunk into the rail. The flange 5 has pivotally mounted therein at 65 7 toothed gripping members 8, which members are adapted to be moved inwardly and outwardly for releasing and holding the window sash. Pivotally connected at 9 to the inner ends of the gripping members 8 70 are inwardly extending links 10, which links extend into the chambered members 11 and have their other ends pivotally connected at 12 to the vertically disposed rock levers 13. The rock levers 13 are pivotally mounted on 75 pins 14 carried by the plate 6, and have their adjacent ends overlapped as clearly shown in Figure 1. Pivotally connected at 15 to the overlapped ends of the rock levers 13 are links 16, which links converge and are 80 pivotally connected at 17 to a slide bar 18. It will be seen that when the slide bar 18 is forced inwardly, the levers 13 will be rocked on their pivotal points 14, thereby imparting pulls on the links 10 and the 85 toothed gripping members 8 will be moved inwardly to inoperative positions out of engagement with the window frame 2 for allowing spring movement of the window sash. It will also be seen that when the toothed 90 bar 18 is pulled outwardly the rock levers 13 will be rocked in a manner whereby the links 10 will be forced outwardly into biting engagement with the window frame 2 for positively holding the window sash against 95 movement, and in any adjusted position. To maintain the parts in inoperative position, coiled springs 19 are provided, which coiled springs are connected at 20 to the rock levers 13, and to the eyes 21 carried by the 100 flange 5 of the plate, therefore it will be seen that when an upward movement is imparted on the handle end of the notched bar 18 for moving the same out of cooperative engagement with the edge 22 of the flange 4, the 105 springs will immediately move apart to inoperative positions.

When it is desired to latch the window the operator grasps the handle member 22 of the notched bar 18, and pulls outwardly 110

thereon, which action will force the gripping members 8, and said gripping members 8 will be held in outward gripping position by the edge 22 of the flange 4 engaging 5 one of the notches 24 of the notched bar. When it is desired to positively lock the bar 18 against movement the plate 25 is moved downwardly into engagement with the upper side of the notched bar and securely held by means of the set screw 26, which extends through elongated slot 27 in the plate and is threaded into the flange 4, therefore it will be seen that the device may 10 be positively locked against movement. 15 From the above it will be seen that a sash fastening and holding device is provided which is simple in construction, positive in its operation and provided with a system of leverage which insures considerable power being applied to the pivoted gripping members 8.

The invention having been set forth what is claimed as new and useful is:—

1. The combination with a window sash, 25 of a sash holding device, said sash holding device comprising a notched bar, a holding means cooperating with the notched bar for holding the same in adjusted position, diverging links pivotally connected to the 30 notched bar, pivoted overlapping rock levers, said diverging links being pivotally connected to the overlapped ends of the rock levers, pivoted window frame engaging members, said window frame engaging 35 members extending towards each other, link connections between the rocking levers and the adjacent ends of the window frame gripping members, and spring means cooperat- ing with the rock levers and normally main-

taining the gripping members out of engagement with the window frame. 40

2. The combination with the side rail of a window sash, of a sash holding device, said device comprising vertically disposed rock levers, the adjacent ends of said rock levers being overlapped, an operating bar, link connections between the operating bar and the overlapped ends of the rock levers, pivoted window frame engaging members, link connections between the window frame 45 50 engaging members and the lock bars and spring means cooperating with the rock bars for maintaining the same in inoperative positions.

3. The combination with the side rail of 55 a window sash, of a sash holding device, said device comprising a plate arching the inner side of the window frame, a flange carried by said plate and engaging the outer side of the rail, a flange carried by said plate and engaging the inner side of the rail, vertically disposed overlapped rock levers carried by the plate and disposed in a recess of the rail, a notched operating 60 65 bar extending through the inner flange of the plate, a detent cooperating with said notched bar for holding the same in adjusted positions, link connections between the rock bars and the notched bar, pivoted window frame engaging members pivotally 70 75 in chambered members carried by the outer flange of the plate and link connections between the outer ends of the rock bars and the pivoted window frame engaging members.

In testimony whereof I hereunto affix my signature.

JOHN RETZLAFF.
